UNITED STATES PATENT OFFICE.

OLIVER S. SLEEPER, OF BUFFALO, NEW YORK, ASSIGNOR TO BUFFALO FOUNDRY & MACHINE COMPANY, OF BUFFALO, NEW YORK, A CORPORATION OF NEW YORK.

MOUNTING FOR FUSION KETTLES.

Application filed November 5, 1919. Serial No. 335,810.

To all whom it may concern:

Be it known that I, OLIVER S. SLEEPER, a citizen of the United States, residing in Buffalo, in the county of Erie and State of New York, have invented new and useful Improvements in Mountings for Fusion Kettles, of which the following is a specification.

This invention relates to a mounting for fusion kettles such as are employed for manufacturing carbolic acid, beta-naphthal, resorcin, nigrosine, and so forth, and it has for its object the provision of simple and efficient means for mounting such kettles on the furnace in a manner which will permit the contents thereof to be quickly and easily discharged without liability of losing any of the material under treatment or endangering the workmen.

20 In the accompanying drawings:

Figure 1 is a top plan view of a fusion kettle mounted on a furnace by improved means which embody my invention. Figure 2 is a vertical longitudinal section of the same.

Similar characters of reference relate to like parts in both figures.

10 represents the outer wall or body of the furnace in which the heat is generated in any suitable manner for fusing the material to be treated. Upon the upper edge of this furnace wall is arranged a supporting frame 11 of metal and preferably of annular form. On the front part of said frame the same is provided with a delivery spout 12 for directing the liquid from the kettle which is being emptied to the receptacle intended to receive the same.

Movably mounted on this frame is a saddle 13 which carries the kettle 14 in which the material is fused over the furnace. This saddle is of annular form and constructed of metal and the same is pivotally connected on its front part with the frame so as to permit of tilting the saddle and associated parts forwardly. This connection is preferably effected by two pivot pins 15 each passing transversely through companion lugs 16, 17, arranged on the front parts of the frame and saddle.

The kettle 14 is arranged with its body within the saddle and supported thereon by an annular external flange or rim 18 arranged on the upper edge of the kettle and seated on the upper side of the saddle.

Upon lifting the saddle on its rear side so that the same tilts forwardly the contents of the kettle will be discharged into the spout and directed by the latter into any receptacle intended to receive the same. This lifting of the saddle and the parts mounted thereon is preferably effected by attaching a hoisting tackle to a pin 19 mounted transversely on a pair of lugs 20 projecting from the rear part of the saddle.

65 The contents of the kettle can by this means be very easily and quickly emptied without liability of losing any of the material or splashing any of the same on the workman, this being particularly important 70 when the liquid under treatment is of a dangerous character.

For the purpose of permitting the contents of the kettle to be readily stirred or agitated if this is required means are provided which are preferably constructed as follows:

21 represents a cross-piece or bridge extending diametrically across the top of the kettle and secured at its opposite ends there-to and provided centrally with an upright bearing 22. Journaled in this bearing is an upright shaft 23 to the lower end of which is secured a stirring or agitating blade 24 of any suitable form. Power may be applied 80 to the upper end of the stirrer shaft in any suitable manner, for instance, as shown in the drawings, by a horizontal shaft 25 journaled in transverse bearings 26 on the cross-piece and provided at its inner end with a bevel gear pinion 27 which meshes with a bevel gear wheel 28 on the upper end of the stirrer shaft while its outer part is provided with a sprocket wheel 29 adapted to receive a sprocket chain driving belt.

85 While the boiling or fusion of the contents of the kettle is progressing that part of the top on opposite sides of the bridge may be covered by means which are so constructed as to permit of pouring the contents 100 of the kettle when desired and also permitting any fumes to escape and be carried away. In their preferred form these means comprise three front cover sections 30, 31, 32, of which the side sections 30, 31 are 105 secured to the top of the kettle and the front part of the bridge and on opposite sides of the spout by screws 33 while the central section 32 forms an easily removable lid which is arranged immediately in rear of 110

the spout and adapted to close the space between the opposing inner edges of the side sections 30, 31. For this purpose the central section 32 rests at its opposite longitudinal edges on two ledges or shoulders 34 arranged on the side cover sections 30, 31. While heating the materials in the kettle the lid 32 is closed but the same is removed prior to pouring the contents of the kettle 10 into the spout. The space over the kettle in rear of the bridge is closed by a rear cover section 35 which is preferably secured to the upper edge of the kettle by screws 36 and which is provided with a vent 15 opening 37 through which the vapors or fumes of the materials under treatment may escape, or be withdrawn and delivered to any suitable place.

The kettle and saddle may be secured to 20 each other by any suitable means to prevent accidental displacement of these parts relatively to each other, this being accomplished for example by means of cleats 38 secured to the top of the saddle by means of screws and 25 overlapping the fixed cover sections of the kettle.

I claim as my invention:

1. The combination of a furnace, a frame mounted on top of the furnace and having 30 a spout, and a kettle pivotally mounted on said frame adjacent to said spout to permit of tipping the kettle toward said spout and discharging the contents of the kettle into said spout.
- 35 2. The combination of a furnace, a frame mounted on top of the furnace and having a spout, a kettle movably mounted on said frame so as to be exposed to the heat of said furnace and capable of being tilted 40 toward said spout for discharging the contents of the kettle into said spout, a cross piece mounted diametrically on the kettle, and a sectional cover mounted on the kettle on opposite sides of said cross piece.
- 45 3. The combination of a furnace, a frame mounted on top of the furnace and having

a spout, a kettle movably mounted on said frame so as to be exposed to the heat of said furnace and capable of being tilted toward said spout for discharging the contents of the kettle into said spout, a cross piece mounted diametrically on the kettle, and a sectional cover mounted on the kettle on opposite sides of said cross piece and comprising three front sections two of which are secured to the kettle on opposite sides of the spout, and a central section which is removably mounted between the opposing inner edges of said side sections. 55

4. The combination of a furnace, a frame 60 mounted on top of the furnace and having a spout, a kettle movably mounted on said frame so as to be exposed to the heat of said furnace and capable of being tilted toward said spout for discharging the contents of the kettle into said spout, a cross piece mounted diametrically on the kettle, and a sectional cover mounted on the kettle on opposite sides of said cross piece and comprising a rear section provided with a 65 vent opening.

5. The combination of a furnace, a frame mounted on the furnace and having a spout, a saddle pivoted on said frame, and a kettle seated in said saddle and tilttable therewith 70 toward said spout.

6. The combination of a furnace, a frame mounted on the furnace and having a spout, a saddle pivoted on said frame, a kettle seated in said saddle and tilttable therewith 75 toward said spout, and means for detachably securing said kettle to said saddle.

7. The combination of a furnace, a frame mounted on the furnace and having a spout, a saddle pivoted on said frame, a kettle seated in said saddle and tilttable therewith 80 toward said spout, cover sections secured to said kettle, and cleats secured to said saddle and overhanging said cover sections and kettle. 85

OLIVER S. SLEEPER.
